UNITED STATES PATENT OFFICE.

DANIEL H. JONES, OF LENOIR CITY, TENNESSEE.

WIRE-STRETCHER.

SPECIFICATION forming part of Letters Patent No. 599,610, dated February 22, 1898.

Application filed February 6, 1897. Serial No. 622,268. (No model.)

To all whom it may concern:

Be it known that I, DANIEL H. JONES, a citizen of the United States, residing at Lenoir City, in the county of Loudon and State of Tennessee, have invented certain new and useful Improvements in Wire-Stretchers; and I do hereby declare the following to be a full, clear, and exact description of the invention, such as will enable others skilled in the art to 5 which it appertains to make and use the same.

This invention relates to improvements in wire-stretching machines, and has more particular relation to machines for stretching wires for wire fences.

15 The invention consists of certain novel constructions, combinations, and arrangements of parts, all of which will be hereinafter more particularly set forth and claimed.

20 In the accompanying drawings, forming part of this specification, Figure 1 represents a perspective view of a machine embodying my invention in operative position for stretching the wires of a fence. Fig. 2 represents an enlarged detail perspective view of one of the 25 wire-clamps, and Fig. 3 represents an enlarged detail perspective view of a modified form of wire-spacing bar.

A in the drawings represents the main frame; B, the supporting-legs; C C, the wind-30 ing-drums; D D, the wire-clamps, and F the spacing-rod. The frame A preferably comprises two side bars a^a , connected at their ends by cross-pieces a^a . The two longitudinal bars a are braced by wires a^2 , connected to their respective ends and passing over suitable blocks a^3 , secured to the rear faces of said side bars. The legs B are pivotally connected to the upper ends of said rails a by bolts b , which pass through any one of the 35 series of apertures b' , formed in the ends of said legs, and through suitable apertures formed in the upper ends of said side bars a . Nuts b^2 , having operating-handles b^3 , are applied on the outer ends of the bolts b to secure 40 the legs in their adjusted positions. To assist in more firmly holding said legs in their proper position for supporting the frame A in an inclined position, said rails a are provided with grooves a^4 , adapted to receive the 45 legs B when they are turned to the desired position. When said legs B are not in use, they are turned down alongside the side of the

frame A and secured in position by hooks and eyes a^5 and a^6 , secured to said legs and said frame, respectively. By means of the apertures b' I am enabled to adjust the legs B upon the frame A, so as to support the latter in the desired position upon hillsides as well as upon level fields. The drums or windlasses C are suitably journaled upon the frame A at pre-55 determined intervals and are each provided with two ratchet-wheels c^c , arranged at their opposite ends and having teeth which extend in opposite directions. Each of said ratchet-wheels c is adapted to be engaged by a pivoted pawl c' , mounted upon the frame A, so that no matter which way the drum is rotated it may be held in position by one of said pawls. The shafts of the drums are extended 60 alternately upon different sides of the frame 65 A and squared, as at c^2 , for the application of an operating-handle c^3 . Each of said drums C is provided with a chain c^4 , secured at one end thereto and at its opposite end to one of the wire-clamps D. Each of said clamps 70 comprises a base-plate d , a rigid block d' , a pivoted lever d^2 , and a guard-plate d^3 . The block d' is intended for the support of the wire that is to be stretched and is formed at its inner end with a plurality of teeth d^4 . The 75 said guard or flange d^3 is mounted upon the base d and projects upward therefrom, so as to form a wire-channel d^5 between it and the side of the block d' . The wire is held in this channel by a turn-button d^6 , mounted upon the block d' . The lever d^2 is pivotally mounted upon said base d at d^7 , and is formed at 80 one end with a plurality of teeth d^8 , adapted to interlock with the teeth d^4 when the lever is pulled toward the same by the wire being 85 pulled through between said teeth.

The ends of the block d' and lever d^2 , respectively, are preferably rounded, so that they come together with a cam action which will jam the wire firmly between them when 90 a pull is exerted upon the base d . The said base d is also provided with a stop d^9 , adapted to limit the movement of the lever d^2 in one direction, so that it cannot pass by the jamming-point with the block d' .

100 Should the free end of the wire extending between the block d' and lever d^2 be pulled, the said lever will immediately turn upon its pivot and permit the wire to freely pass be-

tween it and the block; but any reverse movement of the wire will immediately jam the block and lever together and thus tightly grip said wire. The spacing-bar F for preventing the wires from becoming tangled while being stretched comprises a bar proper, F', and a plurality of spring-rings f', mounted thereon at intervals and adapted to have the wire sprung into the same.

- 10 In the modified form of spacing-bar the bar F' is provided with a plurality of wire-receiving notches f², covered by pivoted plates f³, having operating-handles f⁴ and adapted to be locked in position over said grooves f²
- 15 by angular spring-catches f⁵, secured to said bar F' and adapted to extend through notches f⁶, formed in the ends of said pivoted plates f³, the angular ends of said springs f⁵ entering suitable recesses f⁷, formed in the bar F'.
- 20 It will be observed from this description that the wires, after once being inserted into the recesses or grooves f², are effectively held in position by the plates f³ being turned to permit the spring-catches f⁵ to snap into the notches of the same.

The top of the frame A is provided with two curved guiding-arms a¹, adapted to guide telegraph, telephone, or electric-light wires when the same are being tightened by this apparatus. When the frame A is first set up, before the wires have been tightened, it is preferable to secure the lower end of said frame by pegs or otherwise in position against slipping; but after the pressure is once applied the supporting-legs B, in combination with said frame, form a perfect support. When the wires of the fence are to be stretched, they are inserted, respectively, into the spacing-bars and into their respective clamps D and pulled as tight as possible. The drums C, connected to said clamps D, are then rotated by the crank-handle, thus effectively tightening the wire. The wires are then nailed in position to the post or other place upon which they are to be secured and the machine moved forward again until the desired position has been reached, when the drums C are again loosened to permit the chains to unwind from the same. The wire is then tightened by hand and the drums again rotated to stretch said wire. This operation is continued until the fence is completed.

I do not care to limit the application of my invention to stretching fence-wires, as the same may be aptly employed for stretching telegraph, telephone, electric-light wires, and, in fact, any wires that need such stretching.

By providing the base-blocks and wires a³ and a⁴ upon the back of the frame A the strain upon said frame is equalized and the same effectively braced against bending or giving.

By the employment of my device the wires

may be stretched to any desired degree, even to the point of breaking, as the power of the 65 drums C is practically unlimited because of the rigid formation of the frame and support therefor.

I do not wish to limit my application to any particular number of winding-drums 70 mounted upon the frame A, as the same is governed according to the number of wires that are to be stretched, and may be either the number shown in the drawings or more or less, if desired, or only a portion of the 75 drums mounted on the frame need be used at one time.

It will be observed that, by arranging the protruding ends of the axles of the drums alternately upon opposite sides upon the 80 frame A, a crank-handle of considerable length may be employed without interfering in any way with the next protruding shaft. The grooves a⁴ in which the supporting-legs B are mounted, when in their proper position, 85 have inclined bottoms, so that when the nuts b² are turned home the said supporting-legs are spread, so as to afford a firm support for the frame A and prevent all lateral tipping of the same.

Having thus described my invention, what I claim as new, and desire to secure by Letters Patent, is—

1. In a wire-stretching machine, the combination with a suitable supporting-frame, 95 of a plurality of winding-drums mounted thereon, and wire-clamps connected to said drums respectively and each comprising a base, two cam-levers arranged end to end upon said base, one of the same being rigid and the other pivoted and an angular guard 100 extending longitudinally along the entire upper edge of the stationary lever so as to hold the wire thereon; the construction being such that the wire jams between the peripheries of the respective levers, substantially as described.

2. In a wire-stretching machine, the combination with a suitable frame having grooves formed near one end and provided with inclined bottoms, supporting-legs provided with a plurality of adjusting apertures and mounted in said grooves, adjusting-bolts passing through said supporting-legs and the frame to secure said legs firmly in said grooves 115 so that their lower ends will be spread apart to form a lateral brace and a plurality of winding-drums mounted upon said frame, substantially as described.

In testimony whereof I have signed this 120 specification in the presence of two subscribing witnesses.

DAN. H. JONES.
